(57) **CLAIM**

The ornamental design for an arm chair covering device, as shown and described herein.

DESCRIPTION

FIG. 1 is an elevated perspective view of the arm chair covering device in its folded condition in accordance with my invention;

FIG. 2 is a top view thereof in its unfolded condition;

FIG. 3 is a bottom view thereof;

FIG. 4 is a side view of my invention as shown in FIG. 2, an opposing side view being the mirror image thereof; and, FIG. 5 is an end view, taken from the left side of FIG. 2. The broken lines shown in FIGS. 1-5 are for illustrative purposes only and form no part of the claimed design.
